United States Patent Office.

JAMES H. NORTHCOTT, OF MECHANICSBURG, ILLINOIS.

Letters Patent No. 91,558, dated June 22, 1869.

IMPROVEMENT IN STEAM-PLOWS.

The Schedule referred to in these Letters Patent and making part of the same.

To all whom it may concern:

Be it known that I, JAMES H. NORTHCOTT, of Mechanicsburg, county of Sangamon, and State of Illinois, have invented a new and useful Machine for Plowing or Pulverizing Earth by Steam or other power. I hereby declare that the following is a full, clear, and exact description of the construction and operation of the same, reference being had to the annexed drawings, and the letters of reference marked thereon, making a part of this specification, in which—

Figure 1 is a perspective view.

Figure 2, a view of frame C, guide-wheel F, guide-lever G, and frame D.

Figure 3, a front view of frame C.

Figure 4, a rear view.

Figure 5, a left-side view.

Figure 6, a sectional view of right burden-wheel and axle B.

Figure 7, a sectional view of the working-shaft.

My machine is built on three wheels, two large burden-wheels A, on axle B.

The small or guide-wheel F is connected with axle B by a frame, D, shaped like the letter A. Said guide-wheel is a caster, and the crotched shaft passes up through the front of frame D, rising high enough to receive guide-lever G.

Rising from the vertex of frame C is a sight-post, V. On the front part of frame D is a platform, E. In the centre of platform E, I contemplate a second sight-post. Frame D allows axle B to revolve in the side-bars thereof.

On the axle B, and over frame D, is placed frame C, nearly balanced, and playing freely on said axle.

The front bar of frame C is connected with the cross-bar of frame D by a screw, H, used to elevate and depress the front of frame C. The side-bars of frame C are prolonged to rear of the frame proper. Between these extensions is a hollow shaft, I.

Through said hollow shaft, and through the side-bars of frame C, is passed a solid shaft, W, secured to said hollow shaft by a pin, X. Cast on, or otherwise secured to said hollow shaft, is any required number of disks, (in this machine nine,) marked L.

Secured to these disks are eight cutters, the main working-part of the improvement, and may be called plows. They are formed by a strap of steel, three inches wide, brought into the shape of three sides of a rectangle, one foot long and eight inches wide.

The open end of this cutter is turned to said shaft, and the ends of the two long sides attached to two adjoining disks by dovetails and screws, or otherwise. Said cutters are distributed around said shaft, at an angle of forty-five degrees to each other.

The short side of said cutters makes the under-cut of each slice, and may be called the share. The parallel sides, especially the left arm, make the perpendicular cut, and may be called the coulters.

The edge of the share, in my drawings, is straight, and with the straight-edged share I demonstrated the power of reaction to propel the carriage when the working-shaft is driven by a spring on a platform on said carriage.

I have contemplated, for field-machines, a share with edge shaped like the letter V, with the vertex forward, and also a set of pointed instruments, with eyes like a mattock, for tramped or gravelly earth. The shares should be curved in the line of motion, to about the same arc as the line of motion around the shaft. The width and curve of share should be greater for an engine of low speed than high. The edge of the share should be further from the shaft than the back, as it travels while it revolves. Each cutter cuts eight inches in width and depth, and is marked M. All, except the right-hand one, eight and a half inches clear in width, that the slice may pass freely through. The second extends half an inch into the furrow made by the first. The third, over the second, and so of the rest.

To the left side of the left disk is secured an eccentric, N, by screws, or otherwise, and to said eccentric, a second eccentric, N, to receive connecting-rods from the pistons of any suitable double engine, placed on frame C.

It has been a leading object with me so to combine and arrange the parts of my machine as to receive the power of the engine directly from the piston, on the shaft carrying the cutters, thus passing the power to the main work, without waste, on intervening gearing. Thus, too, the reaction is thrown back on the carriage, without intervening machinery, as a propelling-power in the line of travel.

On the left end of solid shaft W, is pinion K, four inches diameter, working into spur-wheel O, twenty-four inches diameter. On the same shaft with spur-wheel O, cast solid with said wheel, is pinion P, ten inches diameter, working into a cog-rim, cast on or otherwise secured to the left burden-wheel, said cog-rim, forty-two inches diameter. Q, burden-wheel, forty-eight inches diameter.

I call the combination, made up of the hollow shaft, disks, cutters, eccentrics, solid shaft, pin X, and pinion K, the working-shaft. Said shaft receives the power directly from the engine, applies it directly to the main work, and sends the resulting reaction directly to the carriage in the precise line of travel, and, through the gearing, transmits any required power, if reaction be not sufficient, to travel the machine to its feed of six inches to the revolution. The left burden-wheel, receiving motion from the gearing, carries axle B, and, with said axle, a toothed sliding collar, R, on the right end of said axle. This collar ships and unships with the right burden-wheel by lever S, which lever locks said wheel at the same time that it unships said collar.

The lock is effected by said lever falling under catch.

pins U, on the perimeter of said wheel. When collar R is shipped with said wheel, they revolve with axle B. When unshipped, the collar revolves with said axle, and said wheel stands still. Lever S is secured in position by catch T.

Said right wheel, when unshipped, is held from sliding from the inner bar of frame O, by pin Y.

To operate my machine, steam being up, the engineer on platform O, with his box of fuel and barrel or keg of water, by the screw H lifts his cutters above ground. If he is in position for plowing, sees that right wheel is shipped, turns on steam gently, so as to make the under stroke of the shares a back stroke. Then, as near as may be, simultaneously lets the shares into the earth, and lets on full steam. To keep himself accurate in line, he watches sights, and, if need be, works guide-lever G. If he needs to turn his machine, he comes to a slow motion, unships and locks right burden-wheel, when the whole machine revolves on said wheel as a centre, turning to the right. The stroke may be reversed, and turn to the left, by backing. In either way bring the sights to the desired line, reship, and move forward.

The first revolution, the cutters cut a slice, which is the segment of a cylinder, eight inches wide, twenty-two and one-third long, and eight inches thick in the middle. During the revolution, the machine travels forward six inches to the feed.

After the first revolution, each cutter takes a slice somewhat wedge-shaped, fourteen inches long, with an oblique head of surface-earth, eight by six inches, which slice is carried back and dropped with the surface-end in the bottom of the pit from which it is cut, and the subsoil-end overlapping the preceding slice. Said slice fourteen and one-third inches in length, though only partially reversed, amply buries under the subsoil all the sod or surface-earth.

It will readily be seen that no motion is given this soil to the right, or left, or forward, the whole action of the cutters on the earth being first obliquely downward and backward, curving to a horizontal line, and

the last three inches of cutting slightly upward. This motion results in reaction forward and slightly upward, the most advantageous line of action for propelling-power on a machine travelling over a yielding surface.

It will be readily seen, also, that the engine, being brought to bear directly on the working-shaft, exerts more of its power on the earth than if transmitted through gearing, and obviously throws back a correspondingly greater reaction.

Great advantage must result from the broad swath and slow travel secured by this arrangement. I have contemplated one mile of travel per hour, but two sets of cutters, on the same shaft, would, by proper gearing, do the same work with a slower engine and the same travel, while a machine of double the width of swath would do the same work at half-mile travel, or double the work at the same speed.

Most of the parts of my machine have equivalent devices, long in use, but the combination, the process, and the effect are new. Numerous substitutions may be made. A crank and pinion for the screw H. The hollow shaft may be dispensed with, by placing movable half-disks directly on the solid shaft. The right burden-wheel may be otherwise unshipped.

I have contemplated the extension of the rear-ends of the side-bars of the frame O, the lengthening of the arms of the cutters, and a proportionate alteration in the gearing, so as to take any required depth of slice.

1. I claim as new in steam-plowing, the working-shaft, and the combination and arrangement by which said shaft is placed in position to receive the power direct from the engine, with the friction of a single axle between the engine and the main work of moving earth.

2. I claim the frame O, and the mode of raising and lowering the working-machinery as desired, by said frame and the screw H.

May 20, 1868.

JAMES H. NORTHCOTT.
